WILLIAM H. MANNING, OF PONTIAC, MICHIGAN, ASSIGNOR TO GENERAL MOTORS CORPORATION, OF DETROIT, MICHIGAN, A CORPORATION OF DELAWARE

VALVE MECHANISM

Application filed March 1, 1928. Serial No. 258,282.

This invention relates to an internal combustion engine and more particularly to the valve actuating mechanism therefor.

In a poppet valve engine a certain clearance or lash must be allowed between the ends of the valve stems and the tappets or rocker arms, in order to allow the valves to seat when the parts expand as the engine becomes heated. This clearance, which usually approximates eight to fifteen one thousandths of an inch, is objectionable because of the noise it occasions while the engine is warming up and because it results in greater wear on the parts than would occur if a structure with no clearance were feasible.

It is one of the objects of the invention to avoid the necessity of providing valve stem clearance by providing an improved arrangement which will give zero clearance throughout the entire range of temperatures encountered in an internal combustion engine and which will provide a quiet operating means for the valves.

Other objects and advantages of the invention will appear in the course of the following description, taken in connection with the accompanying drawing and appended claims.

In the drawing:

Figure 1 is an end view, partly broken away, of an internal combustion engine embodying my invention.

Figure 2 is an enlarged plan view of the valve operating mechanism, taken on the line 2—2 of Figure 1.

Figure 3 is a side elevation of the valve operating mechanism shown in Figure 2.

Figure 4 is a section on the line 4—4 of Figure 3.

Figure 5 is a side view, with parts broken away, of a portion of the engine illustrating the arrangement of the valves and intake and exhaust ports.

The engine shown is of the conventional L-head type, the intake and exhaust valves 10 and 12 of which are normally held on their seats by the springs 14 and 16 in the usual way. The push rods 18 and 20 are arranged to be actuated by cams 38 and 40 on the shaft 22 by means which will now be described.

Supported in the engine block on the outer side of the cam shaft 22 is a shaft 24 on which are independently journaled the hubs of rocker arms 26 and 28. Journaled on the shaft 24 between the rocker arm hubs is the hub of a T-arm 30 which comprises an arm carrying at its end a cross pin 32. Intermediate its end each of the arms 26 and 28 is formed on its upper surface with a slot 34 for receiving the adjacent end of pin 32. Washers 36 are fixed on shaft 24 on the outer sides of the rocker arm hubs for holding the arms against lateral movement on the shaft.

The outer or free end of arm 28 rests on a cam 40 on the cam shaft, and lying on the surface of the outer end of arm 28 is a wedge 42. Riveted to wedge 42 is a laminated spring 44. By reference to Figs. 2 and 4 it will be noted that spring 44 is bifurcated on the end opposite the wedge for embracing the arm 28 and extending beneath and beyond its hub, the intermediate portion of the spring resting on an end of cross pin 32. On the side distant from the cam shaft, the hub of arm 28 is formed with a boss 46 with an opening for receiving a stud bolt 48. The bolt 48 extends between the furcations of the spring 44 and upon its lower end is threaded bolt 52 provided with flanges for engaging the sides of the spring. With this construction it is apparent that stud 48 may be loosened to permit adjustment of spring 44 and wedge 42 toward and away from push rod 20 for adjusting the clearance between the rod and wedge.

A spring 54 carrying a wedge 56 disposed under push rod 18 is fixed on rocker arm 26 in the same way that spring 44 and wedge 42 are fixed on the arm 28.

The operation of the device will now be described. In "setting" the parts at ordinary temperatures, the studs 48 are loosened and springs 44 and 54 are adjusted so that a zero clearance is provided between the upper surfaces of wedges 42 and 56 and the lower ends of the corresponding push rods 18 and 20. Studs 48 are then tightened. The springs 44 and 54 are then in contact with pin 32. As the cam shaft rotates, the cam 40 lifts the arm 28 to raise the push rod 100

20. As arm 28 lifts, it carries with it the T-arm 30 which also lifts the spring 54, thus withdrawing the wedge 56 from its position between the free end of rocker arm 26 and the lower end of push rod 18. The design of the apparatus, the length of T-arm 30, the slope of the surfaces of the wedges, etc., are such that withdrawal of a wedge by operation of rocker arm 28, produces a clearance between the push rod and rocker arm greater than the maximum decrease in distance between the end of the valve tappet 20 or, in case the valve stem directly engages the wedge, between the end of the valve stem 15 and the surface of the rocker arm upon which the wedge bottoms. This decrease in distance depends upon a number of factors among which are the expansion of the valve stem and tappet and of the cylinder itself. 20 When the rocker arm 28 resumes its lowered position, the pin 32 moves downward and spring 54 pushes wedge 56 outward sufficiently to take up the clearance between the rocker arm and the push rod, the strength 25 of spring 56 being insufficient to overcome the tension of the spring surrounding the valve stem and unseat the valve. Similarly, spring 44 and wedge 42 are operated to adjust the clearance between push rod 20 30 and rocker arm 28 when arm 26 is rocked by the cam shaft.

When the engine is cold and is started running, the lifting of one rocker arm withdraws the other wedge and as the arm lowers, the force of the leaf spring causes the wedge to resume its original position. As the engine heats and the valve stems elongate, the wedges are unable to return to their original position but are held slightly away from it, the leaf springs then remaining slightly spaced from the upper side of pin 32 in the lowest position of the latter.

With the construction described, a condition of zero clearance for both the intake and exhaust valves is maintained, regardless of the temperatures existing. While I have illustrated a push rod interposed between each valve stem and the cam shaft, it is obvious that this is not an essential feature, 45 since the valve stem may extend directly to the spacing wedge without the interposition of a push rod. The expression "valve actuating member" is used in the claims to denote a member which actuates a valve, 50 whether the member is a valve stem, a push rod, a second rocker arm, or other element.

The structure may be modified for adapting it to types of engines other than that illustrated, without departing from the scope 55 of the invention as defined in the appended claims.

I claim:

1. In an internal combustion engine, the combination of two valve actuating members, 60 a pivotally supported rocker arm adjacent

each member and movable with its respective member, a wedge resiliently held between said rocker arm and member, and means operated by rocking of one rocker arm for removing the other wedge from its position relative to the other rocker arm. 70

2. In an internal combustion engine, the combustion of two valve actuating members, a pivotally supported rocker arm adjacent each member and movable with its respective member, a leaf spring fixed to each arm and carrying a wedge interposed between the respective arm and member, means for rocking said arms to actuate the members, and means actuated by rocking of one arm for withdrawing the wedge associated with the other arm. 75

3. In an internal combustion engine, the combination of two valve actuating members, a pivotally supported rocker arm adjacent each member and movable with its respective member, a leaf spring fixed to each arm and carrying a wedge interposed between the respective arm and member, means for rocking said arms to actuate the members, and a pivotally mounted arm carrying a cross pin extending between each rocker arm and its respective spring. 80

4. In an internal combustion engine, the combination of two reciprocable valve actuating rods, a shaft adjacent thereto and carrying rocker arms positioned to move with the respective rods, means for rocking said arms, a leaf spring mounted on each arm and carrying a wedge positioned between the respective arm and rod, an arm rockably supported on said shaft and carrying a pin extending between each rocker arm and its spring. 90

5. In an internal combustion engine, including a reciprocable valve actuating rod, 100 a rocker arm pivotally supported adjacent thereto and movable with said rod, means for rocking said arm, a leaf spring fixed to said arm and carrying a wedge interposed between said arm and rod, and means operated by said engine for intermittently removing said wedge from its position between said arm and rod. 105

6. In an internal combustion engine, including a reciprocable valve actuating rod, 110 a rocker arm pivotally supported adjacent thereto and movable with said rod, means for rocking said arm, a spring pressed element supported on said rocker arm and movable to vary the spacing between the rod and arm, and means operated by said engine for intermittently moving said element to increase said spacing. 115

7. In an internal combustion engine, a pair of rocker arms, a valve actuating member adjacent each rocker arm, a spring pressed element supported between each rocker arm and its respective valve actuating member and movable to vary the spacing therebetween, and means operated by the move- 120

ment of one rocker arm and its associated member for moving the element associated with the other arm to increase the spacing between the other rocker arm and its associated member.

5 8. In an internal combustion engine including a spring pressed valve actuating element, a rocker arm operable with said element, a wedge supported on the rocker arm and positioned between said arm and valve actuating element, and means operating automatically for intermittently moving said wedge in a direction to increase the clearance and returning it to a position to provide a zero clearance between said arm and valve actuating element.

10 9. In an internal combustion engine, a rocker arm and valve actuating member operable therewith, a wedge positioned between said elements for varying the spacing therebetween, a leaf spring connected with said wedge and rocker arm, and means for withdrawing said wedge.

15 10. Valve operating mechanism comprising, in combination with two valves and means for alternately actuating each of said valves, spacing elements movable to a position to take up clearance between each actuating means and its valve, means for resiliently moving said spacing elements to such position, and means actuated by the actuating means for one valve to move the spacing element for the other valve away from such position.

20 11. In a valve actuating mechanism a rocker arm, means for intermittently actuating said arm, a valve actuating member arranged to be actuated by the movement of said arm, a leaf spring secured to said arm and a wedge carried by said spring and positioned between said arm and said valve actuating member.

In testimony whereof I affix my signature.
WM. H. MANNING.
